Primary Examiner — Jonathan J Han*Assistant Examiner* — Amanda J Berlinski(74) *Attorney, Agent, or Firm* — Capitol City TechLaw(57) **CLAIM**

The ornamental design for a NEBULIZER COMPRESSOR, as shown and described.

DESCRIPTION

FIG. 1 is a front, top, and right side perspective view of a NEBULIZER COMPRESSOR showing our new design:

FIG. 2 is a front, bottom, and left side perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is a sectional view taken along line 9-9 of FIG. 3, and omitting inside mechanisms;

FIG. 10 is a sectional view taken along line 10-10 of FIG. 3, and omitting inside mechanisms; and

FIG. 11 is a front, top, and right side perspective view showing an alternate configuration of the first embodiment in which a lid is opened.
